UNITED STATES PATENT OFFICE.

CHRISTIAN PEPER AND CHARLES O. SOBINSKI, OF ST. LOUIS, MISSOURI;
SAID SOBINSKI ASSIGNOR OF ONE-HALF HIS RIGHT TO SAID PEPER.

TRACK-CLEANING ATTACHMENT FOR STREET-CARS.

SPECIFICATION forming part of Letters Patent No. 378,374, dated February 21, 1888.

Application filed December 21, 1887. Serial No. 258,607. (No model.)

To all whom it may concern:

Be it known that we, CHRISTIAN PEPER and CHARLES O. SOBINSKI, both of the city of St. Louis, in the State of Missouri, have invented 5 a certain new and useful Improvement in Track-Cleaning Attachments for Street-Cars, of which the following is a full, clear, and exact description, reference being had to the accompanying drawings, forming part of this 10 specification, and in which—

Figure I is a side elevation of our improved attachment. Fig. II is a top view showing the running-gear of the car. Fig. III is a section taken on line III III, Fig. I.

15 Our present invention relates to a device for lifting the scraper from the track, it being applicable to such a scraper as that shown in the patent issued to us November 18, 1887, No. 372,816; and our present invention consists 20 in features of novelty hereinafter fully described, and pointed out in the claims.

25 Referring to the drawings, 1 represents part of a car. 2 represents the scraper, which is the same in this application as in the patent referred to, and will not be here particularly described. It is provided with a bar or arm, 3, as in the said patent, by which it is connected to the car.

30 Our present invention relates entirely to a means for lifting the scraper from the track when desired, and this means consists of toggle arms or bars 4, pivoted together at 5, and connected to the arm 3 at 6 and to a fixture at 7. The fixture we show consists of a hanger, 35 8, secured to the body of the car. At the lower end of the hanger 8 is pivoted an arm, 9, to the upper end of which is connected one end of a bar, 10, the other end of which is connected at 11 to the upper toggle-arm, 4. There 40 is also pivoted to the hanger 8 an arm, 12, to the upper end of which is connected one end of a pull rod, 13, the other end of which is made fast to a lever, 14, pivoted at 15 to the bottom of the car, the connection at 15 being 45 preferably made by means of a rock-shaft secured to the bottom of the car by means of boxes 16. Connected to this shaft is another arm, 17, to which is connected one end of a rod, 18, made fast at its upper end to the lower 50 end of an operating-lever, 19, pivoted at 20 to

the car, and the upper end of which passes through a guard or yoke, 21, secured to the front or dash board of the car.

We have described the device for raising one of the scrapers; but there are, as shown in Fig. 55 II, preferably two of these scrapers on a car, and the arm 9 of each scraper is preferably made fast to the hanger 8, (there being a hanger on each side of the car,) by means of a rock-shaft, 22, that extends across the car. The 60 preferred connection between the arm 9 on each side of the car and the arm 12 is made by a short sleeve, 23, as shown in Fig. II.

The operation of the device is as follows: 65 When the driver desires to lift the scraper 24 from the ground, he moves the lever 19 in the direction indicated by the arrow in Fig. I, and may engage it behind a shoulder or catch, 24, on the guard 21, as shown in Fig. III, to hold the scraper or scrapers in elevated position. As he moves the lever in this direction, 70 its lower end, the rod 18, the arms 14 and 17, the rod 13, the arms 9 and 12, the toggle bars or arms 4, and the scraper are moved in the direction indicated by the arrows in Fig. I, 75 and the scraper is thus raised from the track, this movement of the lever causing the toggle-arms to be raised through means of the described connection between the toggle-arms and the hanger 8, consisting of the bar 10 and 80 arms 9 and 12. The lifting of the toggle-arms of course lifts the scraper, to which they are connected. To allow the scraper to pass over an obstruction when it is in use without operating the lever 19, we form a slot, 26, in the 85 end of the rod 13, through which the pin passes that connects the rod to the arm 12.

It is evident that the inner end of the bar 10 could be connected to the same arm as the inner end of the rod 13, instead of having a separate arm, as described; and it is also apparent that the inner end of the rod 18 could be connected to the same arm as the outer end of the rod 13.

We claim as our invention—

95 1. In a track-cleaner, the combination of the frame to which the scraper is secured and means for lifting the frame, consisting, essentially, of toggle arms or bars, a bar connected to the toggle-arms, and a lever located at the 100

end of the car, to which said bar is connected by suitable arms and rods, substantially as and for the purpose set forth.

2. In a track-cleaner, the combination of the frame to which the scraper is secured, toggle-arms connecting the frame to a fixed point, a bar connected to the toggle-arms, an arm to which the bar is connected, a hanger to which said arm is pivoted, a second arm pivoted to said hanger, rod connected to said second arm at one end, and a lever to which said rod is connected and by which the parts are operated, substantially as and for the purpose set forth.

15 3. In a track-cleaner, the combination of the frame to which the scraper is secured, toggle-arms connecting the frame to a fixed point, hanger secured to the bottom of the car and to which the toggle-arms are connected at one 20 end, a bar connected to the toggle-arms, arms pivoted to the lower end of said hanger and to one of which said bar is connected, a rod connected at one end to the other of said arms, an arm pivoted to the bottom of the car, to

which said rod is connected, arms pivoted to 25 the front portion of the car, to one of which said rod is connected and to the other of which one end of a rod, 18, is connected, and an operating-lever to which the other end of said rod 18 is connected, substantially as and for the 30 purpose set forth.

4. In a track-cleaner, the combination of the frame to which the scraper is secured, toggle-arms 4, bar 10, hanger 8, to which the toggle-arms are connected, a rock-shaft secured to 35 the lower end of said hanger, an arm, 9, to which the said bar 10 is secured, arm 12, rod 13, one end of which is connected to said arm 12, arm 14, to which the other end of the rod 13 is connected, arm 17, rod 18, and lever 19, 40 all substantially as and for the purpose set forth.

CHRISTIAN PEPER.
C. O. SOBINSKI.
